UNITED STATES PATENT OFFICE.

JOSEPH C. RHODES, GEORGE E. GUFFEY, AND JAMES G. SHEEHAN, OF DANVILLE,
KENTUCKY.

TUNNEL-MASK.

Specification of Letters Patent. Patented Apr. 9, 1918.

1,262,566.

Application filed July 11, 1917. Serial No. 179,901.

To all whom it may concern:

Be it known that JOSEPH C. RHODES, GEORGE E. GUFFEY, and JAMES G. SHEEHAN, citizens of the United States, residing at 5 Danville, in the county of Boyle and State of Kentucky, have invented new and useful Improvements in Tunnel-Masks, of which the following is a specification.

This invention relates to masks designed 10 for use by engineers and other trainmen for protection against gases usually encountered in tunnels and also as a protection against intense heat and escaping steam, or from flying glass caused by the breaking of the water 15 glass, the mask being designed to protect the head of the wearer under any and all conditions.

The primary object of the invention is to 20 provide a head protecting mask, which will supply fresh air to the wearer from a suitable source, such as from a compressed air valve to the locomotive, the air passing from the interior of the mask through a heat insulating chamber formed by a double wall, 25 so that a current of fresh air is continually supplied to the mask and will prevent the heat from passing through the walls and at the same time supply fresh air to the wearer to avoid suffocation.

30 Another object is to provide means at the point of entrance of the air into the insulating chamber, to muffle the sound incident to such entrance, so that the hearing of the wearer will not be interfered with.

35 The mask also provides protection for the ears against harsh sounds of the engine exhaust within the tunnel and the sudden atmospheric change due to the engine leaving said tunnel.

40 The invention further contemplates the provision of novel means for forming the body of the mask by cutting the outer surrounding wall from a single piece of fabric and providing it with gores to form the top and lining said walls with another piece of 45 fabric secured along its top and bottom edges to form a surrounding air or insulating chamber.

With the above and other objects in views 50 the invention consists of the following novel combination and arrangement of parts, hereinafter more fully described and illustrated in the accompanying drawings, in which—

Figure 1 is a perspective view of a mask

constructed in accordance with the present 55 invention;

Fig. 2 is a rear elevation of the same;

Fig. 3 is a central vertical sectional view, a head being shown by dotted lines;

Fig. 4 is a horizontal section; and 60

Fig. 5 is an enlarged fragmentary sectional view through the inlet port of the air chamber, illustrating the muffler located therein and a contiguous part of the supply port. 65

Referring to the drawings in detail, like characters of reference denote corresponding parts throughout the several views.

The invention in its practical form consists of an outer casing formed from a single 70 piece of material, cut to provide an outer wall 10, the upper portion of which is gored as indicated at 11, in order that the same may be formed into the top 12. The outer wall is formed into a substantially circular 75 casing by means of the back seam 13, the mask being of a convenient size to incase the head and extend downward to the shoulders of the wearer. The casing further includes an inner wall 14 cut from a single piece of 80 material and which extends upward and is secured to the outer wall along its top edge, at the point of juncture of the outer wall with the top 12, the securing means being formed of stitches 15. The lower edge of 85 both the inner and outer walls is formed with front and rear downwardly extending points 16 and 17 respectively, to provide upon each side of the mask shoulder receiving recesses 18. The lower edges of the inner and outer walls of the mask are secured together by a binding 19, stitched thereto, so that these two walls provide a surrounding air space or insulating chamber 20 entirely 90 surrounding the mask. 95

The chamber 20 is provided with an inlet port 21, preferably at the front portion of the mask and secured within this port by means of a plate 22 and the packing 23, is an air supply pipe 24, the plate 22 being riveted 100 to a similar plate secured upon the interior of the chamber 20, while the packing 23 is stitched to the outer wall 10.

The air supply pipe 24 is provided with a threaded end 25, for connection with a union 105 26, by means of which there is secured to the pipe 24 a flexible supply pipe 27, adapted to have suitable connection with the com-

pressed air valve of a locomotive or any other suitable source of supply, through the medium of a flexible nipple 28. The union by means of which the pipe 27 is secured to the pipe 24 is provided with the usual gland 29, in order to provide an air tight connection between these two pipes.

The inner wall 14 of the chamber 20 is provided with a plurality of spaced outlet ports 30, which establish connection between the said chamber and the interior of the mask, so that air supplied to the inlet port 21 will circulate through the chamber 20 around the head of the wearer of the mask, escaping into the interior thereof through the ports 30, providing a continuous supply of fresh air to the wearer and also providing a surrounding insulating wall of cool air, for the purpose of protecting the head from heat.

In order to deaden the noise of the compressed air entering the chamber 20, there is provided at the inlet port 21 an air filtering and muffling element 31, shown in the present instance in the form of a sponge, the air entering and passing through this sponge in its passage into the chamber 20, thereby effectually deadening and muffling the sound of its entrance.

Various changes in the form, proportion and details of construction may be made, as for example, the air connection of the mask need not be positioned at the front, this being the preferred location when used by fireman.

It will be seen that the invention provides a simple and efficient protecting mask for the uses and purposes specified and when inflated the inner casing will expand within the space between the outer casing and the head of the wearer, fitting snugly and comfortably around the face and neck, except at the point of the seam 13, so as to cause the mask to adhere and conform to the movements of the wearer's head, keeping the lenses in proper position before the eyes and closing the opening around the neck to prevent the entrance of heat and gas. By these means the fresh air entering through the openings around the head of the wearer will pass downwardly and out through the passage provided along the seam 13, the constant current of fresh air preventing the entrance of foul air into the mask through said passage.

Located within the walls of the mask are side openings 32, which are covered by glass closures 33, which enable the wearer of the mask to see without exposing the eyes to the danger of cinders or other particles. An additional outlet port 34 is provided in the inner wall of the mask, in a position to supply fresh air to the nose of the wearer.

By locating the outlet ports 30 along the upper edge of the surrounding air chamber, the air enters the interior of the mask at a point adjacent the top thereof and is forced downwardly along the line of the seam 13, passing out at the bottom and keeping a current of fresh air passing over the head and face of the wearer.

For convenience, the mask may be provided with means for hanging up the same when not in use, which comprises a ring 40 secured to a tab or loop 41 sewed at the juncture of the gores 11.

It is believed that from the foregoing description, when taken in connection with the accompanying drawings, the construction, operation and advantages of the invention will be apparent. The right is reserved to make such changes in the form and proportion thereof as will fall within the scope of the claims hereto appended.

Having described the invention, what is claimed is:

1. A mask embodying a casing including an outer wall cut from a single piece of material and provided with gores to form the top of the mask, an inner wall cut from a single piece of material and secured along its top and bottom edges within the outer wall to form a surrounding insulating chamber, an inlet port for said chamber and outlet ports also formed in said chamber and communicating with the interior of the mask.

2. A mask embodying a casing including an outer wall cut from a single piece of material and provided with gores for forming the top of the mask, an inner wall cut from a single piece of material and secured along its top and bottom edges within the outer wall to form a surrounding insulating chamber, an inlet port for said chamber and outlet ports also formed in said chamber and communicating with the interior of the mask at a point adjacent the top thereof.

3. A mask embodying a casing including inner and outer walls secured along their upper and lower edges to provide a surrounding air chamber, an inlet port for said chamber, outlet ports also provided in said chamber and communicating with the interior of the mask and means located at the inlet port for muffling the sound of the entering air.

4. A mask embodying a casing including inner and outer walls secured along their upper and lower edges to provide a surrounding air chamber, an inlet port for said chamber, outlet ports also provided in said chamber and communicating with the interior of the mask and means including a filtering element located at the entrance of the inlet port for muffling the sound of the entering air.

5. A mask embodying a casing including inner and outer walls secured along their upper and lower edges to provide a surrounding air chamber, an inlet port for said chamber, outlet ports also provided in said chamber and communicating with the interior of the mask and means including a sponge located at the entrance of the inlet

port for muffling the sound of the entering air. 10

In testimony whereof we affix our signatures.
